UNITED STATES PATENT OFFICE.

WILLIAM A. SCHATZ, OF ASTORIA, NEW YORK, ASSIGNOR OF SEVENTY PER CENT TO
WILLIAM J. ATWOOD, OF NEW YORK, N. Y.

LIQUID DISPENSER.

Application filed January 24, 1923. Serial No. 614,533.

To all whom it may concern:

Be it known that I, WILLIAM A. SCHATZ, a citizen of the United States, residing at Astoria, in the county of Queens and State 5 of New York, have invented certain new and useful Improvements in Liquid Dispensers, of which the following is a full, clear, and exact description, such as will enable others skilled in the art to which it 10 appertains to make and use the same.

This invention relates to liquid dispensing apparatus, and more particularly in some of its details to such an apparatus especially adapted for cooling and dispensing beverages or similar drinks.

It is a general object of the invention to provide a liquid dispensing apparatus of the type having a closed exterior reservoir and an auxiliary reservoir extending into a cooling 20 chamber, with an air-tight joint between the two, and an improved air admitting means carried by the reservoir for the admission of air when liquid is drawn off in such a manner that air pressures within and without the container are readily equalized.

Another object is to provide in an apparatus of the class mentioned an improved arrangement for the admission of air into the liquid container as liquid is drawn off, and at the same time to effect agitation of the liquid within the container.

Other objects will be in part obvious in connection with the following detailed description of an apparatus embodying an exemplification of the invention, and in part pointed out in connection therewith.

The invention accordingly comprises the features of construction, combinations of elements, and arrangement of parts, which will 40 be exemplified in the constructions hereinafter set forth and the scope of the application of which will be indicated in the claims.

For a complete understanding of the nature and objects of the invention, reference 45 should be had to the following detailed description taken in connection with the accompanying drawing, in which there is shown a central vertical section of a dispensing apparatus embodying the invention.

Referring to the drawing for a detailed description of the embodiment shown, a base or supporting receptacle 1 is provided with side walls 2, preferably circular in horizontal projection and preferably also being suitably insulated. This base recep-

tacle has an interior cooling compartment for the reception of a cooling medium, such as ice, and a top 3 and bottom 4 may also be suitably insulated. The top is preferably provided with an opening, with a cover 5 60 for the introduction of ice, for the inspection of the interior parts of the dispenser, and for other purposes. An auxiliary container or cup 6 of earthenware or similar material preferably extends within the cooling compartment being suitably supported therein. An auxiliary wall extends from the bottom of the base 1 so as to contact with the auxiliary container and steady it in position. A discharge conduit 8 communicates 70 with the auxiliary container extending through the cooling compartment and through the wall thereof, terminating in an exterior valve 9.

The auxiliary container traverses the cooling chamber preferably extending through the top 3 thereof and terminating thereabove in an opening having a surrounding flange 10. This opening or mouth may be of any desired shape, but is preferably circular, and seated therein is a resilient washer or gasket 11 of corresponding shape and fitting over the flanged edges of the cup so as to form therewith a liquid and air-tight joint. In the preferred form of the invention the main liquid container 12 rests directly upon the resilient washer 11. The main container may, however, be partially or wholly supported by other means, the desirable feature being the formation of a 80 liquid and air-tight joint between the two containers. The container 12 forms a reservoir for the liquid to be dispensed, and is entirely closed, except for a neck or conduit 13 which extends through the washer 11 90 into the cup 6, and a normally closed opening in the bottom, the purpose of which will be more fully pointed out hereinafter. A glass bottle is preferably employed for the main container, being inverted with the 100 neck extending downwardly into the cup as stated. The weight of the bottle and contents, being thus supported on the resilient washer 11, assists in effecting the liquid and air-tight joint between the main and auxiliary liquid containers. The washer 11 is 105 preferably of soft rubber, so as to intimately contact with the cup and main container under the weight of the latter, effecting the desired liquid and air-tight joint when the 110

bottle is placed in position. A liquid space is thus formed by the main and auxiliary containers, of which the pipe 8 may be considered an extension. When liquid is in the 5 main container, a continuous unbroken liquid column occupies this space at all times, extending from the bottom of the auxiliary container to the surface of the liquid in the main container.

- 10 For the admission of air to the container 12 when liquid is withdrawn, so as to equalize pressures within and without the liquid space, an air-tube 14 is provided communicating with the exterior air pressure 15 and directly with the interior of the liquid space. As shown in the drawing, the bottle 12 is specially formed for supporting this air-tube in an integrally formed seat 15 in the bottom of the bottle, having an opening 20 for the passage of the tube. This seat is formed for the reception of a plug 16, in which the air-tube 14 is mounted in supporting relationship. For this purpose, it is convenient to form the plug 16 with an 25 opening extending therethrough in which the tube is frictionally gripped, so as to have its outer end in communication with the external air. This plug may be removed from its seat 15 when the bottle becomes 30 empty, and the tube removed. The opening in the bottom of the bottle may then be conveniently sealed, as by the insertion of a convenient stopper, so the bottle may be shipped or stored with its liquid contents 35 in the usual manner. The air-tube 14 extends down into the liquid column of the dispenser, preferably extending through the neck of the bottle and terminating well down within the auxiliary container.
- 40 Due to the fact that the resilient washer 11 forms an air-tight seal between the main and auxiliary containers, air cannot enter the neck of the bottle except by the tube 14. The liquid in the auxiliary receptacle will 45 therefore always remain in contact with the neck, rising thereabove to form with the liquid in the main container a continuous unbroken column. As the auxiliary container fills when the main container is inverted thereon in the position shown in the 50 drawing, liquid will pass from the main container to the auxiliary container, filling the latter up to the lower edge of the bottle neck and slightly thereabove, the air in the 55 space above the liquid becoming slightly compressed due to the weight of the liquid column above. An air-chamber is thus provided, which acts as a cushion when flow is checked and tends to equalize the pressure 60 at the draw-off valve 9, consequently resulting in a smooth discharge flow when the valve is opened. Due to the fact that the air-tube 14 extends down within the liquid column, it will be seen that a multitude of 65 small air-bubbles will be discharged from

the lower end of the tube directly into the liquid column whenever liquid is discharged. These bubbles, passing upwardly through the liquid column, result in a particularly advantageous agitation within the liquid 70 column, aerating the liquid in the dispenser and thoroughly mixing the contents in case the liquid is composed of different constituents. It will therefore be seen that it is advantageous to place the discharge from the air-tube well down within the liquid column.

From the above description it will be seen that the operation of the improved dispenser is substantially as in the open top type. The advantages of both the closed and open type of reservoir are thus obtained, while the disadvantages incident to the open type are avoided.

When the bottle or main reservoir 12 is empty, the air-tube is conveniently removed and the seat 15 readily sealed by means of an ordinary cork and the utility of the bottle as a shipping or storing vessel is in no way impaired.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a liquid dispensing apparatus, in combination, a cooling chamber, an auxiliary liquid container extending within said chamber, a closed liquid container forming the main liquid reservoir and having a discharge opening in communication with said auxiliary container, a continuous liquid space being thereby provided for the reception of liquid to provide a continuous liquid column, a liquid and air-tight joint between said liquid containers, and an air-tube carried by said main liquid reservoir and communicating with the exterior air and directly with the liquid of said liquid column for admitting air thereto when liquid is withdrawn, whereby an unbroken liquid column is continuously maintained within said liquid space.

2. In a liquid dispensing apparatus, in combination, a cooling chamber, an auxiliary liquid container extending within said chamber, a closed liquid container forming

- the main liquid reservoir and having a discharge opening in communication with said auxiliary container, a continuous liquid space being thereby provided for the reception of liquid to provide a continuous liquid column, a liquid and air-tight joint between said liquid containers, an air-tube detachably carried by an upper wall of the main reservoir and communicating with the exterior air and with the liquid column well down within the body thereof so air-bubbles therefrom, when liquid is withdrawn, result in effecting agitation of the liquid in said liquid column.
3. In a liquid dispensing apparatus, in combination, a cooling chamber, an auxiliary liquid container extending within said chamber, a bottle forming the main liquid reservoir, having an opening in the bottom thereof, and also having a neck adapted to communicate with said auxiliary container, a continuous liquid space being thereby provided, a resilient sealing member carried by said auxiliary container and forming a seat for receiving the bottle in inverted position to form a liquid and air-tight joint between the main and auxiliary reservoirs, a stopper for the opening in the bottom of said main reservoir, and an air-tube connected to said stopper and extending to a position within the liquid of the liquid column.
4. In a liquid dispensing apparatus, in combination, a cooling chamber, an auxiliary liquid container extending within said chamber and having an opening disposed without said chamber, a closed liquid container forming the main liquid reservoir and having a neck extending into said auxiliary container forming therewith a liquid space or column, a resilient sealing member between said main and auxiliary containers upon which said main container is carried, forming a liquid and air-tight joint between said containers, and an air-tube detachably carried by said main liquid reservoir and communicating directly with the liquid of said liquid space to admit air thereto, whereby an unbroken liquid column is continuously maintained.
5. In a liquid dispensing apparatus, in combination, a main container having a discharge opening, an auxiliary container in communication with said discharge opening so the main and auxiliary containers cooperate to provide a liquid space for a liquid column, and an air-tube supported by said main container and terminating within the liquid of said column for aerating and agitating the same.
6. In a liquid dispensing apparatus, in combination, a main reservoir having open-
ings in remote sides thereof with seats for the reception of closures for sealing the reservoir, and an air-tube adapted to be detachably carried in one of said openings for introducing air into the body of the liquid in the apparatus.
7. In a liquid dispensing apparatus, in combination, an auxiliary reservoir, a main reservoir having a neck opening and a second opening remote therefrom, both of said openings having seats for the reception of closures for sealing the reservoir, the main reservoir being supported with its neck opening in communication with the auxiliary reservoir for discharge of the liquid through said auxiliary reservoir and forming a liquid space, and an air-tube adapted to be carried in said remote opening and terminating within the liquid of said liquid space.
8. In a liquid dispensing apparatus, in combination, an auxiliary reservoir, a main reservoir having a neck opening and a second opening remote therefrom, both of said openings having seats for the reception of closures for sealing the reservoir, the main reservoir being supported with its neck opening in communication with the auxiliary reservoir for discharge of the liquid through said auxiliary reservoir and forming a liquid space, and an air-tube adapted to be detachably carried in said remote opening and extending through said neck opening into the auxiliary reservoir to provide an agitating means when liquid is withdrawn.
9. In a liquid dispensing apparatus, in combination, an auxiliary reservoir, a main reservoir having a discharge opening and a second opening remote therefrom, both of said openings being formed for the reception of closures for sealing the reservoir, a resilient sealing member between the main and auxiliary reservoirs for supporting the former upon the latter with the discharge opening of the main reservoir in direct communication with the liquid of the auxiliary reservoir for discharging through the latter and forming therewith an unbroken liquid column, an air-chamber provided beneath said sealing member and communicating with said liquid column, and an air-tube carried in said remote opening and communicating with the exterior atmosphere and with the liquid in said liquid column.

In testimony whereof I affix my signature, in the presence of two witnesses.
